UNITED STATES PATENT OFFICE.

ROBERT T. JOHNSTON, OF PLAINFIELD, NEW JERSEY, ASSIGNOR TO THE CAMPBELL PRINTING PRESS & MANUFACTURING CO., OF NEW YORK, N. Y., A CORPORATION OF NEW YORK.

SHEET-DELIVERY MECHANISM.

SPECIFICATION forming part of Letters Patent No. 721,893, dated March 3, 1903.

Application filed July 7, 1900. Serial No. 22,866. (No model.)

To all whom it may concern:

Be it known that I, ROBERT T. JOHNSTON, a citizen of the United States, residing at Plainfield, in the county of Union and State of New Jersey, have invented a new and useful Sheet-Delivery Mechanism, of which the following is a specification.

The object of this invention is to provide a new and improved sheet-delivery mechanism especially adapted for use in front of the impression-cylinder of the ordinary printing-press to deliver the sheets printed side up and without contact of the freshly-printed surfaces with any part.

15 The invention consists in arranging a first set of instrumentalities, as tapes, onto which the sheet passes, a second set of tapes intermeshing with the first set, means for reciprocating this second set, and means for raising 20 the second set under the first set to lift the sheet from off the first set, so that the second set can then carry the sheet forward and deliver the same.

The invention further consists of certain 25 novel points of construction hereinafter particularly pointed out, and referred to in the claims.

Referring to the accompanying five sheets of drawings, Figure 1 is a side elevation of 30 an ordinary two-revolution cylinder printing-press with the invention applied thereto. Fig. 2 is a plan of the delivery mechanism with the framework of the machine omitted. Figs. 3, 4, 5, and 6 are elevations illustrating 35 the different positions the parts assume in operation. Fig. 7 is a detail view, on an enlarged scale, illustrating the belt and controlling mechanism which actuates the second set of tapes; and Fig. 8 is a similar view illustrating a modified arrangement of belt which 40 may be used if desired.

Referring to the drawings in detail, A designates the framing, B the impression-cylinder, and C the feed-board, of an ordinary form of 45 printing-press.

50 10 designates a shaft journaled in the framing of the press, on which shaft is mounted a set of tape-pulleys 11. 12 designates another shaft, which is journaled in the framing, on 55 which is mounted a set of tape-pulleys 13.

Tapes D are arranged between the pulleys 11 and 13. These tapes constitute what is hereinafter referred to as the "first" set of tapes. This set of tapes is driven in the usual manner by gearing from the gear carried by the 55 impression-cylinder, as indicated in dotted lines in Fig. 1, so that the top surface thereof will move away from the impression-cylinder at a speed substantially equal to the peripheral speed of the impression-cylinder. 60

A suitable carriage, made up of two light frames E E, is arranged as shown. Each frame has a roll 14, which runs on a track 15, and a roll 16, which runs on a track 17. The tracks 17 17 are arranged on the sides of the 65 delivery-table F. The tracks 15 15 are pivoted, as at 18, to the framing A.

19 designates the cam-shaft of the machine, which is driven by the ordinary gearing to turn continuously during the operation of 70 the press, and if the press is of the ordinary two-revolution type the same is arranged to turn once for each two revolutions of the impression-cylinder or once for each complete forward and backward stroke of the bed. On 75 this shaft is arranged a cam 20, adapted to strike on a roller 21, mounted on a pivoted lever 22, which connects by link 23 to an arm 24, mounted on a shaft 25, journaled in the framing. This shaft 25 carries arms 26, which 80 fit under each of the tracks 15, and by this mechanism the tracks, and thereby the carriage, will be raised, as hereinafter described. On the other end of the shaft 25 is mounted a crank-disk 27, which carries a crank-pin 28, 85 which connects by pitman 29 to an arm or lever 30, mounted on a shaft 31, journaled in the framing. On this shaft 31 are arranged arms 32, which connect by pitman 33 to the carriage-frames E E. By this arrangement 90 the carriage will be reciprocated, as herein-after described.

Arranged in the carriage-frames E E is a shaft 34, on which is arranged a set of tape-pulleys 35. In the forward end of the carriage-frames a tape roller or pulley 36 is journaled. Arranged between the tape-pulleys 35 and the tape-roller 36 is a set of tapes G, which is hereinafter termed the "second" set of tapes. This second set of tapes G is ar- 100

ranged to intermesh with the first set of tapes D, as shown in Fig. 2.

Arranged on the ends of the shaft 34 and the tape-roller 36 are pulleys 37, between which pulleys are arranged strong leather or canvas belts 38. Either or both of these belts are controlled to properly actuate the second set of tapes. This can be done in either of two ways. In Fig. 7 one of the belts 38 is shown as rigidly connected to a bearing-piece 39, which is free to move vertically in a suitable bracket 40, projecting up from the framing. The pulleys 37 for this belt 38 are loosely mounted on the shaft 34 and the shaft of the tape-roller 36.

A ratchet-wheel 41 is arranged on the shaft 34. The pulley 37 on the shaft 34 carries a suitable spring-pressed pawl 42, which engages said ratchet-wheel 41. A pawl 43 may be arranged on the carriage-framing in the position indicated to prevent the said pulley 37 from turning backward. By this arrangement as the second set of tapes moves forward the same will not run on the pulleys 35 and roller 36, as the pawl 42 will turn around the ratchet-wheel 41 without affecting the same; but on the backward stroke—that is, the stroke toward the impression-cylinder—by reason of the fact that said belt 38 is held by the bearing-piece 39 the belt will be actuated to turn the second set of tapes in such way that their top surfaces will remain stationary and their underneath surfaces will run at double the speed of the movement toward the impression-cylinder, whereby the tapes will withdraw from under the sheet to deliver the sheet or to allow it to settle down on the delivery-table. The arrangement of the bearing-piece 39 so as to be capable of a vertical movement provides for the lost motion occasioned by the fact that the carriage is in an inclined position as the same moves forward. This inclined position is desirable, as it keeps the air-pressure on top of the sheet during the forward movement of the carriage.

A modified arrangement of the mechanism for operating the belt is shown in Fig. 8. In this modification the pulleys 37 are fixed on their respective shafts and the piece 39 is provided with a pivoted clutch 44, which carries a small steel spring 45, which is hit by the pulley 37 on the shaft 34 as the carriage reaches the end of its forward movement to cause the clutch to grip the belt for the purpose of holding the same on the backward movement of the carriage. As the carriage starts on its forward movement from its extreme position nearest the impression-cylinder the belt frees itself of the clutch. By this arrangement the second set of tapes G will be properly actuated.

Shafts 46 are generally arranged in the carriage-frames E E, as shown in Fig. 1, to carry a set of guides 47 over the second set of tapes to prevent the sheet from curling up. This set of guides is omitted from Fig. 2 for the sake of clearness.

The delivery-table F is pivoted, as at 48, to the frame, and the same carries suitable struts 49 to hold the same in raised position, as shown in Fig. 1 in dotted lines.

Suitable strippers H are arranged between the first set of tapes and the impression-cylinder in the ordinary manner to direct the sheet from the impression-cylinder down onto said set of tapes.

The operation may be clearly understood from the third and fourth sheets of the drawings, in which a crank-arm is substituted for the crank-disk 27 to more clearly show the various positions. In Fig. 3 the sheet S is shown as having passed down onto the first set of tapes and the second set of tapes as having reached its extreme backward position. In Fig. 4 the second set of tapes has been raised up above the surface of the first set of tapes to pick the sheet off from said first set of tapes, so that the same can be carried forward by the second set of tapes. The carriage then moves forward with the sheet on the second set of tapes, the second set of tapes remaining stationary in the carriage during this movement. This will carry the sheet out over the delivery-board, as shown in Fig. 5. The carriage then retreats or moves backward, and during this movement the belt or belts 38 and the ratchet-and-pawl mechanism will cause the second set of tapes to withdraw from under the sheet to allow the same to settle easily and nicely down upon the delivery-table, as shown in Fig. 6. At or just before the carriage reaches its extreme forward motion the tracks 15 are lowered, so that on the backward movement the second set of tapes will pass under the surface of the first set of tapes to take the next sheet and deliver the same, as before described.

This constitutes a very simple and efficient mechanism for the purpose of delivering sheets printed side up without contact of the freshly-printed surfaces with any part. The device also does away with the use of any grippers to take or control the sheet, the use of such grippers being objectionable, as the same mar or break the edges of the sheets.

It will be noted that the front end of the second set of tapes is entirely free and that there are no tracks or guides which interfere with the sides of the delivery-table. This allows "slip-sheeting"—that is, the introduction of blank or blotter sheets between the printed sheets as they are delivered on the delivery-table, which is sometimes done on very nice work to prevent any smutting.

Another advantageous point of the construction is the pivoting of the delivery-table in the manner shown, which allows it to be raised, so that the inking apparatus, which is generally arranged under the said delivery-table, can be readily got at for adjustment and manipulation. As the delivery-table is raised about its pivots to assume the position shown in dotted lines in Fig. 1 the

carriage-frames E E will turn about the rolls 14 14 to allow the movement thereof which is necessary. The bracket 40 is slotted sufficiently to allow this movement. Thus as the 5 delivery-table is raised no part of the printed-side-up delivery will be disturbed or disconnected, and when the delivery-table is lowered again to its operative position the sheet-delivery mechanism is ready for immediate 10 operation.

The details and arrangements herein shown and described may be greatly varied by a skilled mechanic without departing from the scope of my invention as expressed in the 15 claims.

Having thus fully described my invention, what I claim, and desire to secure by Letters Patent, is—

1. The combination in a sheet-delivery mechanism, of a set of delivery instrumentalities onto which the sheet passes, a set of tapes intermeshing therewith, means for reciprocating the set of tapes, and means for raising the set of tapes when under the delivery instrumentalities to lift the sheet off of the delivery instrumentalities, so that the set of tapes can then carry the sheet forward.

2. The combination in a sheet-delivery mechanism, of a set of delivery instrumentalities onto which the sheet first passes, a set of tapes intermeshing therewith, means for reciprocating the set of tapes, means for raising the same when under the delivery instrumentalities to lift the sheet, so that the tapes 35 can then carry the same forward, and means for controlling the set of tapes so that the same will deliver the sheet on the backward stroke.

3. The combination in a sheet-delivery mechanism of a first set of tapes onto which the sheet passes, a second set of tapes intermeshing with the first set, means for reciprocating the second set, and means for raising the second set when under the first set to 45 lift the sheet off the first set so that the second set can then carry the sheet forward.

4. The combination in a sheet-delivery mechanism, of a first set of tapes onto which the sheet passes, a second set of tapes intermeshing with the first set, means for reciprocating the second set, means for raising the second set when under the first set to lift the sheet off the first set, so that the second set can then carry the sheet forward, and means 55 controlling the second set so that the same will withdraw from under the sheet on the backward stroke and deliver the same.

5. The combination in a sheet-delivery

mechanism, of a first set of tapes onto which the sheet passes, a reciprocating carriage carrying a second set of tapes intermeshing with the first set, and means for raising the carriage when the second set of tapes is under the first set. 60

6. The combination in a sheet-delivery mechanism, of a first set of tapes onto which the sheet passes, a reciprocating carriage carrying a second set of tapes intermeshing with the first set, pivoted tracks on which said carriage runs, and means for lifting said tracks 70 when the second set of tapes is under the first set.

7. The combination in a sheet-delivery mechanism, of a first set of tapes onto which the sheet passes, a reciprocating carriage carrying a second set of tapes intermeshing with the first set, means for raising the second set of tapes when under the first set, a belt on 75 said second set of tapes, and means for holding said belt on the backward movement of 80 the carriage.

8. The combination in a sheet-delivery mechanism, of a first set of tapes onto which the sheet passes, a reciprocating carriage carrying a second set of tapes intermeshing with 85 the first set, means for raising said carriage to an inclined position, a belt on said second set of tapes, and means for holding said belt as the carriage moves backward, said means being adapted to move vertically to adjust 90 itself to the inclined position of the carriage.

9. The combination in a printing-press, of the framing, an impression-cylinder journaled in the framing, a printed-side-up delivery mechanism arranged in front of the impression-cylinder, a delivery-table pivoted to the framing of the machine, and tracks for the delivery mechanism arranged on said table, whereby both the table and tracks can 95 be raised to an inclined position. 100

10. The combination in a printing-press, of the framing, an impression-cylinder journaled in the framing, a printed-side-up reciprocating sheet-delivery mechanism arranged in front of the impression-cylinder, a 105 delivery-table secured to the framing on which the sheets are delivered, and tracks for the reciprocating delivery mechanism arranged directly on the delivery-table.

In testimony whereof I have hereunto set 110 my hand in the presence of two subscribing witnesses.

ROBERT T. JOHNSTON.
